UNITED STATES PATENT OFFICE.

AUGUST DUDA, OF STAUNTON, ILLINOIS.

DESIGN FOR A SPIKE.

58,728.

Specification for Design.

Patented Aug. 30, 1921.

Application filed March 15, 1921. Serial No. 452,546. Term of patent 7 years.

To all whom it may concern:

Be it known that I, AUGUST DUDA, a citizen of Poland, residing at Staunton, in the county of Macoupin and State of Illinois, have invented a new, original, and ornamental Design for Spikes, of which the following is a specification, reference being had to the accompanying drawing, forming part thereof.

The figure is a perspective view of a "spike" showing my new design.

I claim:

The ornamental design for a spike as shown.

In testimony whereof I have affixed my signature.

AUGUST DUDA.
